(57) **CLAIM**

The ornamental design for a faucet, as shown and described.

DESCRIPTION

FIG. 1 is a perspective view of a faucet showing my new design.

FIG. 2 is another perspective view of a faucet.

FIG. 3 is a front view of a faucet.

FIG. 4 is a rear view of a faucet.

FIG. 5 is a left side view of a faucet.

FIG. 6 is a right side view of a faucet.

FIG. 7 is a top view of a faucet.

FIG. 8 is a bottom view of a faucet; and,
FIG. 9 is an enlarged view of a faucet taken from the part in
FIG. 1.

The broken lines illustrate portions of the faucet that form no
part of the claimed design.

1 Claim, 9 Drawing Sheets

FIG. 1

FIG. 2

FIG. 3

FIG. 4

FIG. 5

FIG. 6

FIG. 7

FIG. 8

FIG. 9
